METHOD OF AND MACHINE FOR TREATING SHOES

Archibald C. Smith and Ralph H. Weller, Rochester, N. Y., assignors to United Shoe Machinery Corporation, Borough of Flemington, N. J., a corporation of New Jersey

Application December 29, 1938, Serial No. 248,285

25 Claims. (Cl. 12—51)

This invention relates to methods of and machines for treating shoes to improve their appearance and particularly to methods of and machines for treating the throat portions of shoes including, when they are present, the tongues and eyelet flies.

When shoes, for example Oxford shoes, have been substantially completed, for example when they have reached the packing room, it is often found that the tongues of the shoes are more or less wrinkled and that the eyelet flies are widely separated from each other so that the shoes present an unattractive appearance. The wrinkles in the tongue are generally due to the pressure of the lacing thread used to hold the eyelet flies together during the lasting operation, this lacing thread having been cut and removed before the shoes reach the packing room.

Objects of this invention are to give shoes a more presentable appearance by smoothing and shaping the tongues to remove wrinkles therefrom and by pressing the eyelet flies toward each other into the position they assume when laced.

In one aspect, the invention contemplates a novel method of smoothing and shaping the tongues which comprises supporting the instep portion and the tongue portion of a shoe on a form with a thin plate positioned between the tongue portion and the eyelet flies of the shoe and applying pressure to the portion of the shoe which overlies the thin plate so as to press the eyelet flies of the shoe against the plate and cause the tongue portion of the shoe to be pressed between the plate and the form. In order to expedite the shaping of the tongue by this method, heat may be applied thereto in any suitable manner.

The illustrated embodiment of the machine comprises to form to receive the inner face of the shoe tongue, a metal plate conforming to the form and adapted to be disposed against the outer face of the shoe tongue, and pressing members operated from the two sides of the form and adapted to press the eyelet flies of the shoe against the plate and the plate against the tongue on the form. Thus the shoe tongue is pressed between two shaping surfaces which smooth and iron the tongue to remove wrinkles therefrom and the eyelet flies are pressed into proper relation to the tongue. Preferably both the form and the presser members are heated to improve and expedite the action of the shaping devices.

In the drawings,

Fig. 1 is a perspective view of a machine embodying the present invention;

Fig. 2 is a transverse section of a shoe and the operating instrumentalities of the machine taken while the latter are in operating position;

Fig. 3 is a wiring diagram of the electrical apparatus for heating the form and presser members;

Fig. 4 is a perspective view of a portion of a shoe upper prior to the smoothing of the tongue; and

Fig. 5 is a similar view of the shoe after the tongue has been smoothed in accordance with the present invention.

The illustrated machine for shaping under heat and pressure the throat and instep portions of shoes comprises a frame 10 adapted to be placed on a bench and secured thereto by screws passing through flanges 12 at each side of the frame. Projecting forwardly from the frame 10 is a form 14 which is long enough to receive the tongue portion of a shoe, for example an Oxford shoe, and has an upwardly convex surface corresponding to the instep portion of a foot or last, that is, the shape which should be imparted to the inner face of the tongue to enable it to fit the foot of the wearer. The form may, of course, be given various shapes to meet conditions dictated by the style and size of the shoes to be treated and is shown in the form of a semi-ellipsoid, the cross-section, as shown in Fig. 2, being an ellipse divided on its minor axis which is horizontal. Overlying the form 14 is a plate 16 which may be of bronze or some other resilient material which is a good conductor of heat. The plate conforms in shape to the convex surface of the form 14 and at its rear end is secured to the form by a suitable means such as screws 17. These screws may be left loose, as shown, to facilitate the insertion of a shoe tongue under the plate 16 or the plate may be offset slightly adjacent to the screws for the same purpose. Journaled in the frame 10 are two parallel shafts 18 and 20 which extend longitudinally of the form 14 and are located below the form and at each side thereof. Fixed to the forward end of the shaft 18 is an arm 22 and a similar arm 24 is fixed to the forward end of the shaft 20. A presser member 26 is pivoted at 28 to the arm 22 for limited movement and has a pressing face 30 which is complementary to one longitudinal half of the pressing surface of the form 14. The presser member 26 is maintained with its contoured surface 30 directed toward the form 14 by a spring 32 connected at one end to a downwardly depending ear 34 on the presser member 26 and at the other end to the arm 22 near its axis,

the spring serving yieldingly to hold the presser member 26 with its face 30 in position to engage the form 14, or rather the plate 16 upon the form, as the member is swung toward it. A similar 5 pressing member 36 is pivoted to the arm 24 and a spring 38 similar to the spring 32 is provided to maintain the contoured face 40 of the presser member 36 directed toward the form 14.

The rear end of the shaft 18 has fixed thereto 10 an arm 42 and fixed to the rear end of the shaft 20 is a lever having arms 43, 44, the arm 44 being equal in length to the arm 42 and connected to the arm 42 by a link 46. The arm 44 projects upwardly and the arm 42 downwardly with 15 reference to their respective shafts 20 and 18 and the arms are inclined equally from the vertical so that, when one shaft is rotated, the other shaft will be rotated equally in the opposite direction and hence the arms 22 and 24 will move 20 equally and oppositely toward the form 14 and will simultaneously bring the contoured faces 30 and 40 of the presser members into pressing engagement with the work on the form 14. When this occurs the arms 42 and 44 and the 25 link 46 are so arranged that the arms 42 and 44 will be parallel to each other and will extend in opposite directions from their respective shafts 18 and 20.

To operate the presser members 26 and 36, the 30 lever arm 43 which projects downwardly from the shaft 20 is provided with a roll 48 which is engaged by a cam 50 fixed on a horizontal shaft 52. The shaft 52 is provided with an arm 54 fixed thereon which is connected by a rod 56 to an arm 58 on a rockshaft 60 which is mounted to turn in bearings 62, 64 fastened to the floor. The front end of the rockshaft 60 is provided with two treadles 66, 68, one projecting from each side of the shaft 60. Depression of the 40 treadle 66 will turn the rockshaft 60 in a direction to swing the cam 50 toward the roll 48 of the arm 43 to turn the shaft 20 in a direction to swing the presser member 36 toward the form 14 and at the same time the link 46 will cause 45 the shaft 18 to turn in the opposite direction and swing the presser member 26 toward the form 14.

The portion 70 of the cam 50 which engages the roll 48 during the latter part of the depression of the treadle 66 is substantially concentric with the shaft 52 and accordingly the cam is self-locking to hold the parts in pressing position when the treadle is released. To relieve the pressure, of course, it is only necessary to depress 55 the treadle 68 to turn the rockshaft 60 in the opposite direction and release the cam 50.

When a shoe such as that shown in Fig. 4 is presented to the machine the wrinkled tongue portion T will lie between the form 14 and the 60 plate 16 and the eyelet flies F will be spread apart as indicated in that figure. As the presser members 26, 36 close upon the upper, the eyelet flies F will be swung toward each other by the presser members 26, 36 which will press the flies 65 against the plate 16 and, through the plate 16, will apply pressure to the tongue on the form 14, as indicated in Fig. 2, and, since the form 14 and presser members 26, 36 are preferably heated, the shoe, after remaining under pressure for a short time, will have when removed from the machine the appearance shown in Fig. 5, the tongue T having been given its proper shape and the wrinkles removed therefrom and the eyelet 70 flies F having been closed and depressed toward 75

each other and set in the position which they will assume when the shoe is laced.

It will be seen (Fig. 2) that the parallel shafts 18, 20 are located below the form 14 and are spaced laterally therefrom so that as the arms 22, 24, carrying the presser members 26, 36, swing toward the form the presser members approach the form with a component of downward movement. The presser members therefore apply a substantially even pressure to the top 10 and sides of the form.

As shown in Fig. 2, the form 14 is bored to receive a heating unit 72 and the presser members 26, 36 are each bored to receive a similar unit 74. These units are wired to receive current from a source of supply 76 in accordance with the wiring diagram shown in Fig. 3, the flow of current to the unit 72 in the form being controlled by a rheostat 78 and the current to the units 74, 74 in the presser members which are 20 connected in multiple being controlled by a rheostat 80. The connections to the source of current, as shown in the diagram, are made in a junction box 82 mounted on the frame 10 and a telltale or pilot light 84 is mounted on the 25 box to indicate when a switch 86 is closed.

While the foregoing describes one form of machine by means of which the invention may be carried out it should be understood that the invention may be practised without the use of 30 a machine. Thus, after the shoe has been placed on a form and a thin plate inserted between the tongue and the eyelet flies of the shoe, pressure may be applied manually to the eyelet flies, thus pressing the eyelet flies against the thin plate 35 and causing the tongue to be pressed between the plate and the form.

Having thus described our invention, what we claim as new and desire to secure by Letters Patent of the United States is:

1. In a machine for treating parts of shoes, a member for supporting the instep portion of a shoe and the tongue portion, a metal plate for engagement with the opposite surface of the tongue portion, a block cooperating with said 45 metal plate, and means for causing relative movement of the member and block to press the tongue portion of the shoe between the member and the plate.

2. In a machine for treating shoe parts, a 50 form for supporting the instep portion and tongue portion of a shoe, a presser member substantially complementary to a portion of the work-supporting surface of the form for acting directly upon a portion of a shoe supported on 55 the form, a movable support upon which said presser member is pivotally mounted, a spring for holding said presser member in predetermined position upon the movable support, and means for moving said support to bring the 60 presser member into pressing cooperation with a portion of the work which is supported on the form.

3. In a machine for treating shoes, a member for supporting the instep portion of a shoe, a metal plate arranged for insertion between the tongue portion of a shoe supported by the member and the eyelet flies of that shoe, separate presser blocks engageable with the eyelet flies overlying the metal plate, and means for causing 70 relative movement of the member and the presser blocks to press the shoe parts between the member and the plate and between the plate and the presser blocks.

4. In a machine for treating shoes, a form 75

having approximately the shape of the instep portion of a last, a metal plate conforming to the shape of the form, and separate presser blocks movable toward the form from opposite sides thereof to press shoe parts placed between the form and the plate and between the plate and presser blocks.

5. In a machine for treating shoes to give them their proper shape and remove wrinkles therefrom, a form having a shape to be imparted to the inner surface of a shoe tongue, a plate overlying the form and conforming to the shape thereof, the form and plate being adapted to receive a shoe tongue between them, and presser blocks movable toward the form from each side thereof and arranged to press the eyelet flies of a shoe upper against the plate and the plate against the form.

6. In a machine for treating the instep portions of shoe uppers, a curved form to receive the tongue portion of an upper, a thin plate associated with the form and shaped complementally thereto, a presser member having a curved surface substantially complementary to the surface of the plate, a movable support for said presser member, a pivotal connection between said support and said member, a spring to maintain the presser member in predetermined relation to the movable support, and means for effecting movement of said support to press the tongue portion of the shoe between the plate and the form and another portion of the shoe between the presser member and the plate.

7. In a machine for treating shoes to give them their proper shape and remove wrinkles therefrom, a form for supporting the instep portion of a shoe, a thin metal plate in overlying spaced relation to said form adapted to be inserted between the tongue of a shoe supported by the form and the eyelet flies of that shoe, pressing means engageable with the eyelet flies overlying the thin metal plate, and means for causing relative movement of the form and the pressing means to press the tongue between the form and the plate and the eyelet flies between the plate and the pressing means.

8. In a machine for treating shoes, a form having substantially the shape of the instep portion of the last, a metal plate conforming to the shape of the form, separate presser blocks movable toward and from opposite sides thereof to press shoe parts placed between the form and the plate and between the plate and presser blocks, and means for heating the presser blocks.

55. 9. In a machine for treating shoes, a form to support the tongue of a shoe, a metal plate overlying the tongue and transversely curved to tongue shape, and separate presser blocks movable toward the form from opposite sides thereof to press a tongue placed between the form and the plate and to press eyelet flies placed between the plate and the presser blocks.

10. In a machine for treating shoes to give them their proper shape and remove wrinkles therefrom, a form having a shape corresponding to the inner surface of a shoe tongue, a plate overlying the form and conforming to the shape thereof, the form and plate being adapted to receive a shoe tongue between them, a pair of presser blocks each movable toward the form from one side thereof, and means for operating said presser blocks to press the eyelet flies of a shoe against the plate and to press the plate against the form to shape the tongue.

75. 11. In a machine for treating shoes, a form

having substantially the shape of the instep portion of a last, a metal plate conforming to the shape of the form, separate presser blocks movable toward and from opposite sides thereof to press shoe parts placed between the form and the plate and between the plate and presser blocks and means for heating the presser blocks and the form.

12. In a machine for treating shoes to give them their proper shape and remove wrinkles therefrom, an elongated form having the shape to be imparted to the inner surface of the shoe tongue, a plate overlying the form and conforming to the shape thereof, shafts parallel to the longitudinal axis of the form, arms on the shafts, presser blocks loosely carried by the arms, and means for rotating the arms equally and oppositely to move the blocks toward the form and to press the plate against the form.

13. In a machine for treating the instep and throat portions of Oxford shoes, a form to support the tongue portion of a shoe, a thin metal plate shaped to conform to the form, the plate and form being adapted to receive a shoe tongue between them, presser members each complementary to a longitudinal half of the form, and means for relatively moving the presser members and the form to press the eyelet flies of the shoe upon the plate and to press the plate against the tongue upon the form.

14. In a machine for treating the tongue and eyelet flies of a shoe, a form to receive the tongue, a thin metal plate overlying the tongue and shaped to conform to the form, presser members each complementary to a longitudinal half of the form, and arms carrying the presser members, each of said arms being mounted on an axis extending longitudinally of the form and located below and at one side of the form whereby the presser blocks have a component of movement heightwise of the form to press the eyelet flies of the shoe upon the plate and the plate against the tongue of the form.

15. In a machine for treating the tongue and eyelet flies of a shoe, a form to receive the tongue, a thin metal plate overlying the form and shaped to conform to the form, presser members each complementary to a longitudinal half of the form, arms carrying the presser members and arranged in downwardly diverging relation with respect to the form, said arms being each mounted at its lower end upon an axis extending longitudinally of the form, and manually operated means for moving the arms equally and oppositely to move the blocks toward the form with a component of movement heightwise of the form.

16. In a machine for treating the instep portions of shoe uppers, a form having a surface of revolution to receive the tongue portion of an Oxford shoe, a thin plate overlying the form and shaped to conform thereto, presser members each complementary to a longitudinal half of the work-engaging surface of the form, arms mounted on axes parallel to the longitudinal axis of the form and located below the form, pivotal connections between the arms and presser members, springs to maintain the presser members with their form-engaging faces directed toward the form, and manually operated means for turning the shafts equally and oppositely to move the presser blocks toward the form from each side thereof to press the eyelet flies of the shoe upon the plate and the plate against the tongue upon the form.

17. In a machine for treating the instep portions of shoe uppers, an upwardly convex form to receive the tongue portion of the shoe, a thin plate overlying the form and shaped to conform thereto, presser members which together have surfaces complementary to the form, shafts parallel to the longitudinal axis of the form located below and spaced laterally of the form, arms on said shafts carrying said presser members, a second arm on each of said shafts, a link connecting the arms, and manually operated means for turning one of the shafts to move the presser members toward the form to press the flies of the shoe upon the plate and the plate against the tongue upon the form.

18. In a machine for treating the instep portion of shoe uppers, an upwardly convex form to receive the tongue portion of a shoe, a thin plate overlying the form and shaped to conform thereto, presser members each having a face complementary to a longitudinal half of the convex surface of the form, shafts parallel to the longitudinal axis of the form located below and spaced laterally of the form, arms on said shafts carrying said presser members, a second arm on each of said shafts, a link connecting said arms, the arrangement being such that rotation of one shaft will turn the other shaft equally and oppositely, and means for turning one of the shafts.

19. In a machine for treating the instep portions of shoe uppers, an upwardly convex form to receive the tongue portion of the shoe, a thin plate overlying the form and shaped to conform thereto, presser members which together have surfaces complementary to the form, shafts parallel to the longitudinal axis of the form located below and spaced laterally of the form, arms on said shafts, pivotal connections between the arms and presser members, springs to maintain the presser members with their form-engaging faces directed toward the form, a second arm on each of said shafts, a link connecting said arms, and manually operated means for turning one of the shafts to move the presser members toward the form to press the flies of the shoe upon the plate and the plate against the tongue upon the form.

20. In a machine for treating the instep portion of shoe uppers, an upwardly convex form to receive the tongue portion of a shoe, a thin plate overlying the form and shaped to conform thereto, presser members each having a face complementary to a longitudinal half of the convex surface of the form, shafts parallel to the longitudinal axis of the form located below and spaced laterally of the form, arms on said shafts, pivotal connections between the arms and the presser members, means for yieldingly maintaining the presser members with their faces directed toward the form, a second arm on each of said shafts, a link connecting said arms, the arrangement being such that rotation of one shaft will turn the other shaft equally and oppositely, and means for turning one of the shafts.

21. In a machine for treating the instep portions of shoe uppers, an upwardly convex form to receive the tongue portion of the shoe, a thin plate overlying the form and shaped to conform thereto, presser members which together have surfaces complementary to the form, shafts par-

allel to the longitudinal axis of the form located below and spaced laterally of the form, arms on said shafts, pivotal connections between the arms and presser members, springs to maintain the presser members with their form-engaging faces directed toward the form, a second arm on each of said shafts, a link connecting the arms, and a manually operated cam for turning one of the shafts to move the presser members toward the form to press the flies of the shoe upon the plate and the plate against the tongue upon the form.

22. In a machine for treating the instep portion of shoe uppers, an upwardly convex form to receive the tongue portion of a shoe, a thin plate overlying the form and shaped to conform thereto, presser members each having a face complementary to a longitudinal half of the convex surface of the form, shafts parallel to the longitudinal axis of the form located below and spaced laterally of the form, arms on said shaft, pivotal connections between the arms and the presser members, means for yieldingly maintaining the presser members with their faces directed toward the form, a second arm on each of said shafts, a link connecting said arms, a projection on one shaft, and a cam for engaging the projection to turn one of the shafts.

23. In a machine for treating the instep portion of shoe uppers, an upwardly convex form to receive the tongue portion of a shoe, a thin plate overlying the form and shaped to conform thereto, presser members each having a face complementary to a longitudinal half of the convex surface of the form, shafts parallel to the longitudinal axis of the form located below and spaced laterally of the form, arms on said shafts, connections between the arms and the presser members, a second arm on each of said shafts, a link connecting said arms so that rotation of one shaft will turn the other equally and oppositely, a projection on one of the shafts, a cam having a concentric portion arranged for rotation to engage said projection and to be self-locking when the presser members are in pressing position, and means for rotating the cam in either direction.

24. A method of treating parts of shoes which comprises supporting the instep portion and the tongue portion of a shoe on a form, causing a thin plate to be positioned between the tongue portion and the eyelet flies of the shoe, and applying pressure to the portion of the shoe overlying said thin plate so as to press the eyelet flies of the shoe against the plate and cause the tongue portion of the shoe to be pressed between the plate and the form.

25. A method of treating parts of shoes which comprises supporting the instep portion and the tongue portion of a shoe on a form, causing a metal plate to be positioned between the tongue portion and the eyelet flies of the shoe, applying pressure to the portion of the shoe overlying said metal plate so as to press the eyelet flies of the shoe against the plate and cause the tongue of the shoe to be pressed between the plate and the form and simultaneously applying heat to the portions of the shoe undergoing treatment.
